ELECTRONIC PULSE GENERATOR

Bertram Wellman, Lincoln, Mass., assignor to The
Electrodyne Company, Boston, Mass., a corpora-
tion of Massachusetts

Application September 12, 1946, Serial No. 696,590

11 Claims. (Cl. 171—97)

1

The present invention relates to apparatus for generating and controlling electric impulses of non-sinusoidal configuration, particularly with steep fronts.

In various fields of applied electricity it is desirable to work with electric impulses of the above mentioned configuration, of adjustable duration and frequency, and applicable singly, in groups, or automatically repeated at an adjustable frequency. Such impulses are for example used as stimuli in certain physiological tests, where they are applied with stylus probes to nerve or muscle tissue. The usefulness of such tests depends a great deal upon the easy adjustability, within wide ranges, of impulse strength and frequency, and also on the possibility of applying single impulses with the same equipment from which impulse series or groups are derived.

It is one of the principal objects of the present invention to provide a simple, comparatively inexpensive, and yet rugged, dependable and adaptable apparatus for generating electric impulse series or single impulses which reach their maximum value very rapidly and decay immediately upon having reached that value.

Other objects are to provide electronic apparatus which generates with a minimum of circuit elements non-sinusoidal electric impulse series of controllable duration and frequency, of selectively predetermined polarity, of selectively adjustable energy contents, and if desired accompanied by synchronized but independently generated signal impulses; to provide apparatus of the above mentioned type which permits, selectively with the aid of a simple change-over control, the generation either of single impulses or impulse groups or of an infinite series of impulses of similar characteristics but predetermined frequency; and to provide a circuit which, upon operation of a control switch, delivers a single steep front impulse which can only be repeated after resetting of the switch.

In one of its aspects, the apparatus according to the invention employs an electron discharge device having anode and cathode connected to a source of direct current and a control electrode which is maintained at a substantially constant potential, impedance means and a switch in the connection from the cathode to the negative side of the source, current transmitting means in the connection from the anode to the source, and capacitor means connected between the cathode and the positive side of the source.

In another aspect the arrangement according to the invention provides auxiliary, for example

signal impulses which are in exact synchronism with the principal impulses, by way of discharging an auxiliary or signal capacitor through a discharge tube which is triggered by a control electrode connected to the network carrying the main or principal impulses.

In a further aspect, the circuit according to the invention supplies a single electric energy impulse or a predetermined number of such impulses, by means of an electric discharge device having anode and cathode connected to a direct current source and a control electrode, a capacitor in the connection from the cathode to the positive side of the source, another capacitor in the connection between the cathode and the negative side of the source, these capacitor means being so dimensioned that the simultaneous charging thereof across the source causes discharge of the first mentioned capacitor through the discharge device whose control potential depends upon the potential of the cathode and hence upon the relation of the potential drops across the two capacitors. The second capacitor continues to be charged during the discharge or discharges of the first condenser, until it brings the cathode potential close enough to the electrode potential to render discharge of the first capacitor impossible, thus terminating impulse generation. If the second capacitor is small enough for the purpose, discharge of the first capacitor is only locked after a group of impulses (their number depending upon the relative values of the circuit elements) has been generated.

Additional features of the circuit according to the invention are selection of polarity of the impulses by means of a switch in the secondary circuit of a transformer link in the output circuit, and selective supply of either an unlimited series of impulses or one or a predetermined number of impulses whereby all circuit elements which are employed for furnishing the unlimited impulse series are also utilized for operation with one or a preselected number of impulses, the change from one operation to the other being provided by switch means rendering the above mentioned second capacitor ineffective for the purpose of generating an unlimited sequence of impulses.

These and other objects, aspects and features will appear from the following description of a typical, practical embodiment illustrating the novel characteristics of my invention. This description refers to a drawing in which—

Fig. 1 is the circuit diagram of a stimulator for physiological test purposes, constructed according to the present invention;

Fig. 2 is a diagram illustrating the configuration of the impulses furnished by apparatus according to Fig. 1; and

Fig. 3 is a component of the circuit diagram of Fig. 1, illustrating the operation of this circuit when set for delivery of a single impulse or of a limited series of impulses.

In the stimulator according to Fig. 1, a transformer T, supplied from terminals a, c of a standard alternating current supply line, feeds into a conventional rectifying circuit Nr with rectifier tube V, filter network Nf and direct current terminals d, c. Transformer T also supplies, through terminals h1 and h2, the heating elements of the thermionic tubes of the circuit proper now to be described.

An electric discharge device G1, for example of the gas filled thermionic type, is with its anode a1 connected to the positive direct current wire d, through the primary Tp of impulse transformer T1 which constitutes the effective load of tube G1. The control electrode g1 of impulse control tube G1 is connected to a tap p1 intermediate to voltage apportioning resistors R1, R2 which are connected across the direct current supply d, c, thus being supplied with constant voltage and retaining grid G1 at substantially constant potential. The cathode k1 is connected to a point p2 of a discharge and timing network Nt.

The discharge network Nt incorporates a main capacitor C1 which is connected between terminal p2 and supply line d and bridged by a safety resistor R3. Between terminal p2 and the other direct current supply terminal c are connected, through a starting switch S, a resistor R4, and a resistor R5 which is adjustable, having for example a movable tap v. A point p3 between resistors R4 and R5 is connected to the "off" terminal of switch S through a control capacitor C2, this "off" terminal being also connected to a contact t which can be joined to the negative supply wire c by way of movable tap v which, when contacting t, leaves adjustable resistor R5.

An intermediate tap p4 of transformer primary Tp is connected to the positive supply wire d, whereas transformer secondary Ts is connected through a pole changing, double pole double throw switch s1, to the output or probe network Np. An indicator lamp Gl, for example of the gaseous discharge type, may be connected to output wire o.

In order to permit selection of suitable output voltages, network Np incorporates voltage dividing resistors R7, R8 of different values, and selected by means of a switch s2. For fine adjustment of the voltage an adjustable resistor R9 with tap w is provided in series with R7 or R8. For the purpose of impedance matching a resistor R10 may be provided which is connected in parallel to R8 and R9 when switch s2 incorporates R8 in the output network. The main output terminals 11, 12 are connected to tap w and supply wire c, respectively.

For the purpose of providing auxiliary impulses, the following signal network Ns is provided. An electric discharge tube G2, for example of the gas filled thermionic type, is with its anode a2 connected to the direct current supply wire d, through limiting resistor R11. The anode connection contains further the primary of a signal transformer T2 whose secondary feeds into signal output terminals 15, 16. A signal capacitor C3 is connected between a point p5 between transformer T2 and resistor R11, and supply wire c. The control electrode g2 of tube G2 is connected

to the end terminal of transformer T1, through resistor R15 and capacitor C5. A point p6 intermediate capacitor C5 and resistor R15 is connected to supply wire c through a control resistor R16. The cathode k2 of tube G2 is connected to negative supply wire c through capacitor C8 which is bridged by resistor R18.

The arrangement according to Fig. 1 operates as follows, assuming first that it is desired to deliver a continuous series of impulses.

With alternating current supply line ac energized, the cathodes of tubes G are heated and ready for operation, and the direct current supply system d, c, is supplied through networks Nr and Nf. Tap v is disconnected from the "single" operation contact t and connected to a selected section of R5, so that control capacitor C2 is effectively disconnected from the circuit.

When switch S is moved from the "off" to the "on" position, capacitor C1 charges at a rate determined by the setting of tap v on adjustable resistor R5, and the value of fixed resistor R4. With capacitor C1 charging, the potential of cathode k1 becomes more negative relatively to the constant potential of control electrode g1, and when the proper voltage between k1 and g1 is reached, tube G1 will fire. Capacitor C1 thereupon rapidly discharges through the circuit C1—G1—Tp—d—C1, its maximum voltage being almost immediately applied to primary Tp. The discharge impulse is transmitted through secondary Ts and switch s1 to the probe network Np, where it appears at output terminals 11, 12 with the polarity and voltage selected by means of switches s1, s2 and tap w. The discharge continues with a periodic decay, until the impulse ceases altogether when the potential of point p2 and of cathode k1 has become more positive, approaching that of grid g1 sufficiently to render the tube non-conductive.

With switch S left in "on" position, condenser C1 again charges, and cathode k1 becomes more negative until the next impulse begins with C1 again discharging through G1.

By reversing switch s1, the polarity of the impulses can be changed. The gaseous discharge lamp Gl indicates to the operator the occurrence and polarity of each individual impulse. The resistor R3 prevents through comparatively gradual discharge a possible accidental sudden discharge of capacitor R5 if leaks should be present in the circuit.

The impulses available at terminals 11, 12 have the approximate configuration indicated in Fig. 2, with steep wave fronts and aperiodic decay flanks. The spacing of the impulses, or in other words the frequency of the impulse series can be regulated by way of varying the value of the charging impedance R4, R5, as by shifting tap v of resistor R5. The length of the impulses depends upon the characteristics of the above mentioned discharge path of capacitor C1. Although for most purposes the precise length of each impulse is not critical, it can be controlled by varying the impedance of that path.

The arrangement according to Fig. 1 may be used as above described, without network Ns including tube G2, transformer T2, and terminals 15, 16. It is, however, often desirable to have available impulses which are exactly synchronized with, but are otherwise, such as regarding their energy, independent of the output impulses proper. Such auxiliary impulses are for example used for energizing a relay magnet which in turn operates an impulse indicating signalling de-

vice or apparatus for marking a recording strip with timing indicia.

The signal network N_s operates as follows.

The impulse due to the discharge of capacitor C_1 through transformer T_1 causes current to flow through control resistor R_{16} which raises the potential of point p_6 and of grid g_2 sufficiently to cause firing of tube G_2 . Capacitor C_3 , which is normally charged due to its connection between wires d and c of the direct current supply, thereupon discharges through tube G_2 and transformer T_2 , delivering an auxiliary impulse at terminals 15, 16.

If it is desired to deliver a single impulse or a predetermined number of impulses, for instance, a group of two or three impulses, switch S is moved to the "off" position, and tap v is brought into contact with "single" terminal t , connecting control capacitor C_2 between cathode k_1 and supply terminal c . This mode of operation will be explained with particular reference to Fig. 3 which shows capacitor C_2 in effective connection, with contacts v and t in electric contact.

When switch S is moved from the "off" to the "on" position, both capacitors C_1 and C_2 begin to charge.

If the capacitance value of capacitor C_2 is so selected that it will not be fully charged before the firing voltage between cathode k_1 and grid g_1 is reached, the potential of p_2 will remain sufficiently low to cause firing of tube G_1 , and repeated firing thereof, until capacitor C_2 is charged sufficiently to raise the potential of p_2 and of cathode k_1 to a value approaching that of the potential of g_1 so that tube G_1 becomes non-conductive.

If capacitor C_2 is large as compared to C_1 , the latter will discharge several times before C_2 is sufficiently charged to render the tube non-conductive. On the other hand, if the value of C_2 is so selected that the voltage between k_1 and g_1 is below the firing value just after C_1 has once discharged, a single impulse will be delivered before C_2 is sufficiently charged to bring cathode and grid potentials close enough to render tube G_1 non-conductive. By properly selecting, or adjusting the value of capacitor C_2 , discharge of single impulses, or of groups of a pre-selected number of impulses can be provided. In order to repeat this mode of operation, the switch S has to be brought into "off" position, and then back into "on" position to re-initiate the single impulse or impulse group discharge as above described.

A practical apparatus according to Fig. 1 comprises the following circuit elements:

Tubes

V	Type 5Y3GT
G ₁	Type 884
G ₂	Type 2050

Resistors

R ₁	ohms	150,000
R ₂	do	470,000
R ₃	megohms	22
R ₄	ohms	330,000
R ₅	megohms	20
R ₇	do	1.5
R ₈	ohms	130,000
R ₉	do	15,000
R ₁₀	do	15,000
R ₁₆	do	25,000

6 Capacitors

C ₁	mfd	0.5
C ₂	mfd	0.1
C ₃	mfd	25

It should be understood that the present disclosure is for the purpose of illustration only and that this invention includes all modifications and equivalents which fall within the scope of the appended claims.

I claim:

1. Apparatus for generating controlled electric impulses, comprising a source of direct current having a positive output terminal and a negative output terminal; an electric discharge device having an anode, a cathode and a control electrode; circuit making means including a resistor connecting the cathode with the negative output terminal; a transformer having a secondary, and a primary with a terminal connected to said anode and an intermediate tap connected to said positive output terminal of said source; main output terminals connected to said secondary; means for maintaining the electrode at substantially constant positive potential of lesser magnitude than that of the positive terminal; a discharge network including a capacitor; and an auxiliary signal circuit including an electric discharge tube having a cathode connected to the negative terminal, a control electrode connected to the other terminal of said primary and an anode, an output circuit connecting the tube anode to the positive terminal, and auxiliary output terminals coupled to said output circuit.
2. Apparatus for generating controlled electric impulses, comprising a source of direct current having a positive output terminal and a negative output terminal; an electric discharge device having an anode, a cathode and a control electrode; circuit making means including a resistor and a starting switch connecting the cathode with the negative output terminal; a transformer having a secondary and a primary with a terminal connected to said anode and an intermediate tap connected to said positive output terminal of said source, main output terminals connected to said secondary; voltage apportioning means for maintaining the electrode at substantially constant positive potential of lesser magnitude than that of the positive terminal; a discharge network including a capacitor between said cathode and said positive terminal; and an auxiliary signal circuit including an electric discharge tube having a cathode connected to the negative terminal, a control electrode connected to the other terminal of said primary and an anode, an output circuit connecting the tube anode to the positive terminal, and auxiliary output terminals coupled to said output circuit.
3. Apparatus for generating controlled electric impulses, comprising a source of direct current having a positive output terminal and a negative output terminal; an electric discharge device having an anode, a cathode and a control electrode; circuit making means including a resistor and a starting switch connecting the cathode with the negative output terminal; a transformer having a secondary, and a primary with a terminal connected to said anode and an intermediate tap connected to said positive output terminal of said source; main output terminals connected to said secondary; means for maintaining the electrode at substantially constant positive potential of lesser magnitude than that of the positive terminal; a discharge network including a capacitor;

and an auxiliary signal circuit including an electric discharge tube having a cathode connected to the negative terminal, a control electrode connected to the other terminal of said primary and an anode, an output circuit including capacitor means and transformer means connecting the tube anode to the positive terminal, and auxiliary output terminals coupled to said transformer means.

4. Apparatus for generating controlled electric impulses, comprising a source of direct current having a positive output terminal and a negative output terminal; an electric discharge device having an anode, a cathode and a control electrode; circuit making means including a resistor and a starting switch connecting the cathode with the negative output terminal; a connection between said anode and said positive terminal; load means in said anode connection; means for maintaining the electrode at substantially constant positive potential of lesser magnitude than that of the positive terminal; a connection including capacitor means from said cathode to said positive terminal; and capacitor means in said circuit making means between said cathode and said negative terminal, said capacitor means being so dimensioned one relatively to the other that the simultaneous charging thereof initiates a predetermined number of discharges of said first mentioned capacitor means through said load means, said second capacitor charging during said discharges to the locking potential between said cathode and said electrode, when said discharges are terminated.

5. Apparatus for generating controlled electric impulses, comprising a source of direct current having a positive output terminal and a negative output terminal; an electric discharge device having an anode, a cathode and a control electrode; circuit making means including a resistor and a starting switch connecting the cathode with the negative output terminal; a connection between said anode and said positive terminal; transformer means in said anode connection; voltage apportioning means for maintaining the electrode at substantially constant positive potential of lesser magnitude than that of the positive terminal; a connection including capacitor means from said cathode to said positive terminal; and capacitor means connected in series with said resistor and said switch between said cathode and said negative terminal; said capacitor means being so dimensioned one relatively to the other that the simultaneous charging thereof upon closing of said switch initiates a predetermined number of discharges of said first mentioned capacitor means through said transformer means, said second capacitor charging during said discharges to the locking potential between said cathode and said electrode, when said discharges are terminated.

6. Apparatus for generating electric impulses, comprising a source of direct current having a positive output terminal and a negative output terminal; an electric discharge device having an anode, a cathode and a control electrode; circuit making means including a resistor and a starting switch connecting the cathode with the negative output terminal; a connection between said anode and said positive terminal; load means in said anode connection; means for maintaining the electrode at substantially constant positive potential of lesser magnitude than that of the positive terminal; a connection including capacitor means from said cathode to said positive terminal;

and capacitor means in said circuit making means between said cathode and said negative terminal, said capacitor means being so dimensioned one relatively to the other that the simultaneous charging thereof initiates a single discharge of said first mentioned capacitor means through said load means, said second capacitor means having upon said single discharge reached a charge large enough to maintain said cathode at locking potential relatively to said electrode.

7. Apparatus for generating electric impulses, comprising a source of direct current having a positive output terminal and a negative output terminal; an electric discharge device having an anode, a cathode and a control electrode; circuit making means including a resistor and a starting switch connecting the cathode with the negative output terminal; a connection between said anode and said positive terminal; transformer means in said anode connection; voltage apportioning means for maintaining the electrode at substantially constant positive potential of lesser magnitude than that of the positive terminal; a connection including capacitor means from said cathode to said positive terminal; and capacitor means in said circuit making means between said cathode and said negative terminal; said capacitor means being so dimensioned one relatively to the other that the simultaneous charging thereof initiated by said starting switch and controlled by said resistor causes a single discharge of said first mentioned capacitor means through said transformer means, said second capacitor means having upon said single discharge reached a charge large enough to maintain said cathode at locking potential relatively to said electrode.

8. Apparatus for providing an electric impulse, comprising a source of direct current having a positive output terminal and a negative output terminal; an electric discharge device having an anode, a cathode and a control electrode; circuit making means including a resistor and a starting switch connecting the cathode with the negative output terminal; a connection between said anode and said positive terminal; load means in said anode connection; means for maintaining the electrode at substantially constant positive potential of lesser magnitude than that of the positive terminal; a connection including capacitor means from said cathode to said positive terminal; and capacitor means in said circuit making means between said cathode and said negative terminal; said capacitor means being so dimensioned one relatively to the other that the simultaneous charging thereof causes discharge of said first mentioned capacitor means through said load means, said second capacitor means attaining upon a predetermined number of discharges a charge large enough to render said discharge device non-conductive by maintaining said cathode at locking potential relatively to said electrode; and circuit modifying means for rendering said second capacitor means ineffective for the purpose of maintaining said discharge device conductive.

9. Apparatus for providing an electric impulse, comprising a source of direct current having a positive output terminal and a negative output terminal; an electric discharge device having an anode, a cathode and a control electrode; circuit making means including a resistor and a starting switch connecting the cathode with the negative output terminal; a connection between said anode and said positive terminal; load means in said

anode connection; means for maintaining the electrode at substantially constant positive potential of lesser magnitude than that of the positive terminal; a connection including capacitor means from said cathode to said positive terminal; and capacitor means in said circuit making means between said cathode and said negative terminal; said capacitor means being so dimensioned one relatively to the other that the simultaneous charging thereof upon closing said switch causes discharge of said first mentioned capacitor means through said load means, said second capacitor means attaining upon a predetermined number of discharges a charge large enough to render said discharge device non-conductive by maintaining said cathode at locking potential relatively to said electrode; and means for shunting said second capacitor means to render it ineffective for the purpose of maintaining said discharge device conductive.

10. Apparatus for providing an electric impulse, comprising a source of a direct current having a positive output terminal and a negative output terminal; an electric discharge device having an anode, a cathode and a control electrode; circuit making means including a resistor and a starting switch connecting the cathode with the negative output terminal; a connection between said anode and said positive terminal; load means in said anode connection; main output means connected to said load means; means for maintaining the electrode at substantially constant positive potential of lesser magnitude than that of the positive terminal; a connection including capacitor means from said cathode to said positive terminal; capacitor means in said circuit making means between said cathode and said negative terminal, said capacitor means being so dimensioned one relatively to the other that the simultaneous charging thereof upon closing said switch causes discharge of said first mentioned capacitor means through said load means, said second capacitor means attaining upon a predetermined number of discharges a charge large enough to render said discharge device non-conductive by maintaining said cathode at locking potential relatively to said electrode; circuit modifying means for rendering said second capacitor means ineffective for the purpose of maintaining said discharge device conductive; and an auxiliary signal circuit including an electric discharge tube having a cathode connected to the negative terminal, a control grid connected to said load means and an anode, an output circuit connecting the tube anode to the positive terminal; and auxiliary output means coupled to said output circuit.

11. Apparatus for providing an electric impulse, comprising a source of direct current hav-

ing a positive output terminal and a negative output terminal; an electric discharge device having an anode, a cathode and a control electrode; circuit making means including a resistor and a starting switch connecting the cathode with the negative output terminal; a connection between said anode and said positive terminal; transformer means in said anode connection; main output terminals connected to said transformer means; voltage apportioning means for maintaining the electrode at substantially constant positive potential of lesser magnitude than that of the positive terminal; a connection including capacitor means from said cathode to said positive terminal; capacitor means connected in series between said cathode and said negative terminal, said capacitor means being so dimensioned one relatively to the other that the simultaneous charging thereof upon closing said switch and controlled by said resistor causes discharge of said first mentioned capacitor means through said load means, said second capacitor means attaining upon a predetermined number of discharges a charge large enough to render said discharge device non-conductive maintaining said cathode at locking potential relatively to said electrode; means for shunting said second capacitor means to render it ineffective for the purpose of maintaining said discharge conductive; and an auxiliary signal circuit including an electric discharge tube having a cathode connected to the negative terminal, a control grid connected to said transformer means and an anode, an output circuit connecting the tube anode to the positive terminal; means for applying to said control grid a potential derived from said transformer means; and auxiliary output terminals coupled to said output circuit.
